(57) **CLAIM**

I claim the ornamental design for a portable generator, as shown and described.

DESCRIPTION

FIG. 1 is a front perspective view of a portable generator showing my new design;

FIG. 2 is a rear perspective view from above of the claimed design of FIG. 1;

FIG. 3 is a right side view of the claimed design of FIG. 1;

FIG. 4 is a front view of the claimed design of FIG. 1;

FIG. 5 is a left side view of the claimed design of FIG. 1;

FIG. 6 is a rear view of the claimed design of FIG. 1;

FIG. 7 is a top view of the claimed design of FIG. 1;

FIG. 8 is a bottom view of the claimed design of FIG. 1; and

FIG. 9 is a front perspective view from above of the claimed design of FIG. 1 in a second configuration.

FIG. 10 is a front perspective view from above of a second embodiment of the claimed design;

FIG. 11 is a rear perspective view from above of the claimed design of FIG. 10;

FIG. 12 is a right side view of the claimed design of FIG. 10;

FIG. 13 is a front view of the claimed design of FIG. 10;

FIG. 14 is a left side view of the claimed design of FIG. 10;

FIG. 15 is a rear view of the claimed design of FIG. 10;

FIG. 16 is a top view of the claimed design of FIG. 10; and,

FIG. 17 is a bottom view of the claimed design of FIG. 10. The broken lines shown represent unclaimed subject matter and form no part of the claimed design.
